US00D788301S

(12) **United States Design Patent** (10) **Patent No.:** **US D788,301 S**
(45) **Date of Patent:** **** May 30, 2017**

(54) **DRILL**

(71) Applicant: **Gyrus ACMI, Inc.**, Southborough, MA (US)

(72) Inventors: **Kevin C. Edwards**, Olive Branch, MS (US); **Jay A. Casey**, Memphis, TN (US); **Peter Wong**, Arlington, TN (US); **Jesse Conrad**, Cordova, TN (US); **Manfred Held**, Hamburg (DE); **Ronny Staps**, Hamburg (DE)

(73) Assignee: **GYRUS ACMI INC**, Southborough, MI (US)

(**) Term: **14 Years**

(21) Appl. No.: **29/524,744**

(22) Filed: **Apr. 23, 2015**

(51) LOC (10) Cl. **24-02**

(52) U.S. Cl.

USPC **D24/146**

(58) **Field of Classification Search**

USPC D24/146, 147, 148, 113, 133, 137, 138; D8/61, 68; 606/45, 49, 109, 162; 604/35

(57) **CLAIM**

The ornamental design for a drill, as shown and described.

DESCRIPTION

FIG. 1 is a perspective view of drill.

FIG. 2 is a top elevational view of FIG. 1.

FIG. 3 is a bottom elevational view of FIG. 1.

FIG. 4 is a side elevational view of FIG. 1, the other side being a mirror image.

FIG. 5 is an enlarged scale rear elevational view of FIG. 1.

FIG. 6 is an enlarged scale front elevational view of FIG. 1.

FIG. 7 is a perspective view of the drill in an environmental use.

FIG. 8 is a top elevational view of FIG. 7.

FIG. 9 is a bottom elevational view of FIG. 7.

FIG. 10 is a side elevational view of FIG. 7, the other side being a mirror image.

FIG. 11 is an enlarged scale rear elevational view of FIG. 7.

FIG. 12 is an enlarged scale front elevational view of FIG. 7.

FIG. 13 is a perspective view of the drill in a second environmental use; and,

FIG. 14 is a perspective view of the drill in a third environmental use.

The broken lines shown in FIGS. 1-6 illustrate portions of the drill that form no part of the claimed designs. The broken lines shown in FIGS. 7-14 illustrate the drill in an environment of use and forms no part of the claimed design.

1 Claim, 8 Drawing Sheets
